DESIGN FOR A HOUSING FOR WOOD PLANING MACHINE

Edward Yager, Toledo, Ohio

Application May 8, 1945, Serial No. 119,450

Term of patent 7 years

(Cl. D93—2)

To all whom it may concern:

Be it known that I, Edward Yager, a citizen of the United States and a resident of Toledo, Lucas County, Ohio, have invented a new, original, and ornamental Design for a Housing for Wood Planing Machine, of which the following is a specification, reference being had to the accompanying drawing forming a part thereof.

In the drawing, the figure is a perspective view of the housing for a wood planing machine showing my new design.

The left side of the machine is substantially like the right side shown.

I claim:

The ornamental design for a housing for a wood planing machine, as shown and described.

EDWARD YAGER.
